UNITED STATES PATENT OFFICE

CLAUDE C. CALKINS, OF SPOKANE, WASHINGTON

SHOE BEARING

Application filed November 26, 1929. Serial No. 409,988.

My present invention relates to improvements in shoe bearings for agricultural machinery in which the shoe is designed to sustain a bearing supporting a rotary part, operative beneath the surface of the ground. The invention is especially adapted for use in connection with rotary rod weeders of the general type utilizing a sub-surface rotating rod for engaging weeds or other plant growth, to tear them out and leave them on the surface of the ground, at the same time working the ground to a mulch to conserve the moisture beneath the surface. In agricultural implements of this character, bearings which must sustain the rotating rod are mounted in a shoe which is formed to ride beneath the surface of the soil and help to maintain itself in that desired position, and which, because of the dirt and grit encountered, must be protective to the bearings and eliminate as much friction between the bearings and the soil as possible. In bearings for this purpose, it has been found that much dirt will ordinarily enter between the stationary and moving parts and rapidly cut out or choke the bearing, making the rotary act a difficult one.

In my present invention, it is an object to provide a shoe and a bearing in which the wearing parts can easily be replaced when worn, and in which the structure is so designed that any dirt or similar substances entering between the bearing surfaces will work its way out, leaving the bearing clear and providing self-cleaning means for this purpose.

Another object of my invention is to provide a bearing in a shoe that will offer little or no obstruction as the shoe passes through the soil, and means whereby the journal of the said bearing may be retained free to rotate, but protected against longitudinal travel.

And another object of my invention is to provide a bearing eliminating in a large degree any pressures or contact with the dirt in its passage therethrough, and which may be removed for replacement with a minimum of time consumed in that operation.

In its more detailed nature the invention

comprises certain novel features of construction, combination and arrangement of parts, all of which will be first fully described and then be specifically pointed out in the appended claims and illustrated in the accompanying drawing in which:—

Figure 1 is a perspective view of one of my improved shoe bearings, the supporting standard or bar being indicated in part thereon, as is also the rotatable weeder rod.

Figure 2 is a fragmentary cross-sectional view through the bearing, taken on the vertical center therethrough.

Figure 3 is a side elevation of the removable bearing member and showing the rotatable rod in cross-section within its journal.

Figure 4 is a left side elevation of the shoe with parts broken away to disclose the self-cleaning features.

Figure 5 is a cross-sectional view taken on the line 5—5 of Figure 4.

The invention comprises the relatively stationary body portion or shoe 10. This shoe, so-called, is formed with a pointed and somewhat shovel-shaped and projecting end 11, which assists in placing the shoe below the surface of the soil when the weeder to which it is attached and of which it is a part is advanced. This nosing, because of its formation, aids in depressing a rotary member or rod 12, which is supported in the shoe through the rotating journal member 13 which is supported within the shoe for rotative action therein.

The journal for said bearing member is formed partly in the shoe 11 and partly by a removable bearing member 14. On the rear end of the shoe is provided a lateral recess 15 for receiving a bar 16 which is attached to the weeder frame and is formed into what is usually termed a goose-neck. This member is secured to the shoe by the bolts 17 and its forward end abuts against a shoulder 19 of the removable bearing block 14 and acts as a backing or support for said bearing block when it is properly assembled.

A part of the bearing is formed in the shoe structure as at 20 and has a groove 21 approximately central between the sides of the shoe. Co-acting with this portion of the bearing is

the removable bearing block 14 which makes up the other half of the bearing and which in turn has a groove 22 located to align with the groove 21 in the fixed bearing section 20 when the bearing is properly assembled.

5 The complementary grooves 21 and 22 preferably have angular sides, with the bottom of the groove forming the narrowest portion.

10 The bearing block 14 may be formed of any proper bearing material, metal or otherwise, and since this member must take most of the wear as the thrust on the bearing is directly against this member, it is made a part which is easily replaceable when it becomes 15 too much worn to practically serve its purpose.

15 The bearing-member 14 is provided with an extension member 23 with a notch 24 in its end and is designed to fit into a corresponding recess 25 in the shoe, with the side faces of the bearing flush with the side faces of the shoe. This bearing block 14 is also provided with upper and lower flanges 26 and 27 which fit into corresponding parallel recesses 28 and 29 tangential to the journal opening in the shoe to aid in locating this adjustable bearing block and maintaining it flush with the shoe when in place. Thus when the movable bearing block is in place, 20 the bar 16 is secured to the shoe 10 by the bolts 17, the forward one of which engages through the notch 24 of the removable bearing block and clamps the block in position. Rotatable within this bearing thus formed, between the shoe and the removable member 30 is a round journal member or sleeve 13, which is formed with a bore square in cross section to receive the rotating bar 12. Upon the periphery of the journal member 13 is a central, annular rib 31, formed with inwardly sloping sides or tapered in cross section to correspond with the groove 21 in bearing section 20, and the corresponding groove 22 in the removable bearing block 14.

35 45 This journal member 13 has also the same width as the shoe and the bearing, so that a smooth surface is provided along the sides of the shoe in order to eliminate an accumulation of dirt or resistance to progress.

50 55 Through the bottom of the shoe, and opening into the bearing, is a vertical passage 32, and on the bottom face of the shoe is a groove 33 extending from the passage 32 rearward of the shoe for some distance, to provide a pocket into and through which the dirt and débris that may enter the bearing may fall to provide the self-cleaning features of the bearing.

60 The removable bearing block 14 is also provided with a vertical groove 34 semi-circular in cross section and communicating with the passage 32 to allow freedom for passage of dirt or the like from the bearing into and through the passage 32 and into the space or pocket 33 in the bottom of the shoe.

The under face of the shoe is provided with a slightly curved surface and somewhat turned up on the forward end so as to aid in running over any solid obstruction that it may meet in its passage through the soil.

70 In machines of the type using rotating rods below the surface of the ground, it is necessary to maintain considerable pressure to keep the rod below the surface, and since the rods are of considerable length, it is usual to provide three or four such shoes and bearings to properly support the revolving member.

75 By providing a long tapering nose as 11, well below the center of the bearing, I am enabled to materially aid the holding of the rod in its desired position. The nose 11 will part the soil to allow the shoe and the goose-neck 16 to pass through the soil.

80 85 From the foregoing description, taken in connection with the accompanying drawing, it is thought the complete structure, operation and advantages of my invention will be readily understood by those skilled in the art.

90 What I claim is:—

1. A bearing of the character described comprising a shoe, a fixed bearing element, a replaceable bearing element, flanges on one side of the latter engaging recesses in the shoe, a shoulder on the replaceable bearing element, an inset extension member on said replaceable element, a supporting bar abutting said shoulder and overlapping the extension, and means for fastening the bar to said shoe.

100 2. A bearing of the character described comprising a shoe, an integral bearing section on the shoe, a complementary replaceable bearing section, a journal member rotatable in the bearing, a retaining rib on said member engaging grooves in the bearing sections, and each of the bearing sections having openings to form a single dirt-cleaning passage extending through the bottom of the shoe.

105 110 3. A bearing for a rotary weeder comprising a shoe and a bearing section formed thereon, a replaceable bearing section, a journal member rotatable in the bearing, a retaining rib on said member engaging complementary grooves in the bearing sections, each of the bearing sections having an opening forming a single dirt-cleaning passage from the bearing, and said shoe having a bottom groove extending rearwardly from said passage.

115 120 125 4. The combination with a shoe having an integral grooved bearing section and a side recess, of a removable bearing block having a complementary grooved bearing section and a rear extension on the block forming a shoulder, a support located in said recess, overlapping the extension and abutting said shoulder, bolts for securing said support, shoe and extension, a journal member rotatable in the bearing sections, and a central annular rib

on said member located in said grooved sections.

5. The combination with a shoe having an integral grooved bearing section, a side recess and upper and lower parallel recesses, of a removable bearing block having a complementary grooved bearing section, upper and lower flanges seated in the parallel recesses, said block having a rear, inset extension forming a shoulder and a bolt-notch in the extension, a support located in the side recess, overlapping the extension and abutting said shoulder, fastening bolts securing the support to the shoe and one of said bolts engaging said notch, a round bearing sleeve rotatable in the bearing sections, a central exterior, annular rib on said sleeve rotatable in the grooved sections, said shoe having a vertical passage from the bearing and a rearwardly extending, bottom groove communicating with the passage, and said block having a vertical groove communicating with the passage.

In testimony whereof I affix my signature.

CLAUDE C. CALKINS.
